CLAIM

The ornamental design for the combined glassware with embedded crystal quartz apple as shown and described.

DESCRIPTION

FIG. 1 is a perspective front left side view of a combined glassware with embedded crystal quartz apple.

FIG. 2 is a perspective extreme left side view of the combined glassware with embedded crystal quartz apple.

FIG. 3 is the perspective extreme right side view of the combined glassware with embedded crystal quartz apple.

FIG. 4 is the front view of the combined glassware with embedded crystal quartz apple.

FIG. 5 is the back view of the combined glassware with embedded crystal quartz apple.

FIG. 6 is the top view of the combined glassware with embedded crystal quartz apple; and,

FIG. 7 is the bottom view of the combined glassware with embedded crystal quartz apple.

The broken lines in the drawings depict portions of the combined glassware with embedded crystal quartz apple that form no part of the claimed design.
